COMBINED WIPER AND REST FOR SOLDERING TOOLS

Robert C. Edgerton, Wichita, Kans., assignor to Vanguard
Electronic Tools, Inc., Newton, Kans., a corporation
of Kansas

Filed Aug. 29, 1966, Ser. No. 3,627

Term of patent 14 years

(Cl. D26—1)

FIG. 1

FIG. 2

FIG. 3

FIG. 4

FIGURE 1 is an isometric view of a combined wiper and rest for soldering tools, showing my new design;
FIGURE 2 is an enlarged side elevational view;

FIGURE 3 is a front elevational view; and

FIGURE 4 is a top plan view.

I claim:

The ornamental design for a combined wiper and rest for soldering tools, substantially as shown.
